(57) **CLAIM**

The ornamental design for a vaporizer base, as shown and described.

DESCRIPTION

FIG. 1 is a perspective view of the vaporizer base;
FIG. 2 is a front elevational view of the vaporizer base of FIG. 1;
FIG. 3 is a rear elevational view of the vaporizer base of FIG. 1;
FIG. 4 is a left side elevational view of the vaporizer base of FIG. 1;
FIG. 5 is a right side elevational view of the vaporizer base of FIG. 1;
FIG. 6 is a top plan view of the vaporizer base of FIG. 1;
FIG. 7 is a bottom plan view of the vaporizer base of FIG. 1;
FIG. 8 is a perspective view of a second embodiment of the vaporizer base;
FIG. 9 is a front elevational view of the vaporizer base of FIG. 8;
FIG. 10 is a rear elevational view of the vaporizer base of FIG. 8;
FIG. 11 is a left side elevational view of the vaporizer base of FIG. 8;
FIG. 12 is a right side elevational view of the vaporizer base of FIG. 8;
FIG. 13 is a top plan view of the vaporizer base of FIG. 8; and,
FIG. 14 is a bottom plan view of the vaporizer base of FIG. 8.
The broken lines in the drawings illustrate portions of the vaporizer base that form no part of the claimed design.

1 Claim, 4 Drawing Sheets
